UNITED STATES PATENT OFFICE.

WILLIAM LAY, OF KREMLIN, OKLAHOMA TERRITORY, ASSIGNOR OF FIVE-SIXTHS TO W. D. CORNELIUS, H. H. WATKINS, AND W. E. COGDAL, OF ENID, OKLAHOMA TERRITORY.

MEANS FOR TRANSMITTING POWER.

SPECIFICATION forming part of Letters Patent No. 662,077, dated November 20, 1900.

Application filed June 1, 1900. Serial No. 18,759. (No model.)

To all whom it may concern:

Be it known that I, WILLIAM LAY, a citizen of the United States, residing at Kremlin, in the county of Garfield, Oklahoma Territory, 5 have invented new and useful Improvements in Means for Transmitting Power, of which the following is a specification.

This invention relates to new and improved means for transmitting power, and it is especially adapted for use in imparting motion to propellers and similar means for driving vessels, &c. The invention is also applicable to vehicles of various forms.

The primary object of the invention is to 15 provide a strong and simple device of this character by means of which the propeller or other device to which motion is imparted may be revolved without the use of toothed gears and whereby the motion thereof may be 20 quickly reversed without stopping the engines or reversing their motion.

A further object is to provide friction-gears having means of peculiar construction whereby the same are held in contact by means of 25 air or other similar pressure.

To these ends the invention consists in providing a propeller-shaft upon which are mounted friction-gears adapted to contact with other gears mounted at each side of said 30 shaft and receiving motion from engines in any suitable manner. The gears upon the shaft are slidably mounted thereon and connected to a rod or other similar device which is slidably mounted within the propeller-shaft, the ends of which project into chests 35 formed on each end of the propeller-shaft. These chests receive air under pressure from a pump which is operated by the propelling-engines.

40 The invention also consists in the further novel construction and combination of parts hereinafter more fully described and claimed, and illustrated in the accompanying drawings, showing the preferred form of my invention, and in which—

45 Figure 1 is a plan view of the device. Fig. 2 is a longitudinal section showing the propeller-shaft partly in elevation and partly in section. Fig. 3 is an enlarged section through 50 one end of the propeller-shaft, showing the

cylinder and the connection between the sliding friction-disk and the rod. Fig. 4 is a section through the three-way valve, and Fig. 5 is an enlarged section through the opposite end of the propeller-shaft and its cylinder. 55

Referring to said figures by numerals of reference, 1 1 1 are suitable standards having cross-strips 2, within which is journaled a hollow propeller-shaft 3, which is prevented from moving longitudinally in any desired 60 manner. This shaft projects at each of its ends into a cylinder 4, one of which is secured to an end standard 1 and the other to a hanger 5, at the propeller end of the shaft, by means of bolts or in any other suitable manner. A 65 rod 6 extends through this shaft and is provided at each end with a piston-head 7, which bears upon a sliding block or piston 8, provided with suitable packing 9 and having a concaved outer face 10, as shown. A spring 70 11, which may be of any desired form, bears upon the end of the shaft 3, and the head 7 of the rod serves to hold said heads normally removed from the ends of the shaft.

A suitable number of sleeves 12 are slidably 75 mounted upon the shaft, and to each sleeve, at each end thereof, is secured a beveled friction disk or gear 13. A cross-pin 14 is secured within each of these disks 13 and extends through a slot 15, which is formed within 80 the shaft 3 and is secured to the sliding rod 6. It will be understood that each of the friction-disks is secured to the same rod, and all are adapted to be moved at the same time and for the same distance. 85

The friction-disks 13 are arranged in pairs, with their beveled faces oppositely disposed, each pair adapted to be thrown into contact with propelling friction-disks 16, which are mounted upon opposite sides of the shaft 3. 90 These disks are secured to shafts 17, which are journaled within the outer and inner side strips 18 and 19, respectively, connecting the standards 1. A crank 20 is formed at the outer end of each of these shafts, and the 95 cranks upon each side of the frame inclosing the shaft 3 are connected by a rod 21, as shown. A pitman 22 connects each set of driving-disks 16 with a cross-head 23, which is secured to a piston movable within a cyl- 100

inder 24. One cylinder is preferably provided for each set of propelling-disks; but said cylinders are adapted to receive steam from the same supply, and their pistons are 5 driven alternately, but at the same speed. A pipe 25 opens into a cylinder 29, which is mounted above a chest 26 and communicates therewith through a port 28, having a suitable check-valve therein. An exhaust 27 is also 10 provided within the chest 26. The pipe 25, as shown in Fig. 2, is provided with a check-valve which is adapted to prevent the escape of air through said pipe after the same has been drawn into the cylinder. A piston 30 15 works within the cylinder and is connected by means of a pitman 31 to a gear 32, which receives motion from a similar gear 33, which is mounted upon a short shaft 34, having a beveled pinion 35 thereon. This pinion receives motion from gears 36, which are mounted upon shafts 37, each of which is provided with a crank 38, secured to one of the connecting-rods 21. It will thus be seen that motion will be imparted from the engine 24 20 to the pump-piston 30 while the propelling-disks 16 are being revolved. A pipe 39 extends from the chest 26 into one end of the cylinder 4 upon the standard 1, and a three-way valve 40 is located within said pipe at 25 its point of connection with an exhaust 43. A pipe 41 extends from the reservoir 26 to the opposite end of the propeller-shaft 3 and into the chest 4, which is secured to the hanger. This pipe is also provided with a 30 three-way valve similar to that shown in Fig. 4 and having an exhaust, as heretofore described.

It will be seen that motion will be imparted to the friction-disks 16 and to the pump-piston 30 through its gears 32, 33, 35, and 36 at 40 the same time from the pistons within the cylinders 24 and that said friction-disks must be driven in opposite directions in order that motion may be imparted from the oppositely-disposed gears 36 to the intermediate gear 35. The reciprocating motion of the piston 30 of the pump will, as is obvious, draw the air into the cylinder through the pipe 25 and compress the same into the compartment 26, from which 45 the valve 27 will permit it to escape when the pressure reaches the danger-point.

The friction-gears 13 are held normally out of contact with the propelling-disk 16 by means of the springs 11, heretofore referred 50 to. When it is desired to drive the propeller in one direction, one of the valves 40 is turned, for instance, so as to direct air from the pipe 39 into the chest 4, which is secured to the standard 1. The valve 40 within the pipe 41 is at the same time so arranged as to permit the air to exhaust through its outlet 43. The pressure of air upon the piston or sliding block 8 will cause the same to move the 55 rod 6 longitudinally within the shaft 3, carrying therewith the friction-disks 13 and throwing one disk of each pair into contact with its propelling-disks 16. The pressure of the

air upon the piston 8 will obviously promptly clamp these disks together, and it will be seen that motion will be imparted from the 70 propelling-disks 16 to disks 13 and thence to the propeller-shaft 3. It will be seen that the valve 27 will permit the escape of surplus air while the disks are being clamped firmly together. When it is desired to reverse the movement of the propeller, the valve 40 of the pipe 41 is turned so as to direct air into its chest 4, which is secured to the hanger 5, and will thereby throw the rod 6 and the disks secured thereto in the opposite direction, clamping them firmly upon the propeller-disks, as heretofore described. It will be understood that the air which is left within the first-named cylinder will escape through the exhaust in its valve 40. 85

While I have shown and described this device as utilizing air for forcing the piston 8 and the rods 6 back and forth within the shaft 3, I do not limit myself thereto, as water or any other desired fluid may be employed. 90

In the foregoing description I have shown the preferred form of my invention; but I do not limit myself thereto, as I am aware that modifications may be made therein without departing from the spirit or sacrificing 95 the advantages thereof, and I therefore reserve the right to make such changes as fairly fall within the scope of my invention.

Having thus described my invention, what I claim as new, and desire to secure by Letters 100 Patent, is—

1. The combination with a propeller-shaft; of friction-disks adjacent thereto; means for imparting motion to said disks; disks slideable upon, and adapted to revolve with, the 105 propeller-shaft; a rigid connection between the last-named disks, a piston-head connected to the disks; and means for directing pressure upon each of the piston-heads. 110

2. The combination with a propeller-shaft; of friction-disks adjacent thereto; means for imparting motion to the disks; friction-disks slideable upon, and movable with, the propeller-shaft; a rod connecting the slideable disks; 115 a piston-head at each end of the rod, each piston-head movable within a chest; and means for directing pressure upon either of said piston-heads. 120

3. The combination with a frame; of a hollow propeller-shaft journaled therein; friction-disks journaled within the frame at opposite sides of the shaft; means for imparting motion to said disks; disks slideable upon, and movable with, the propeller-shaft; a rod 125 within said shaft and connecting the slideable disks; a piston-head at each end of the rod; a chest for each piston-head; a pipe connecting each chest with a reservoir; a pump opening into the reservoir; and means for operating said pump. 130

4. The combination with a frame; of a propeller-shaft journaled therein; friction-disks journaled within the frame at opposite sides of the shaft; cranks upon the shafts of the

- friction-disks; rods connecting said cranks; cylinders; cross-heads thereto; means for connecting said cross-heads and the connecting-
5 rods; a pump-cylinder; a piston therein; a pinion operated by the connecting-rod; gears receiving motion from said pinion and adapted to operate the pump-piston; friction-disks 10 slideable upon, and movable with, said propeller-shaft; a rod connecting said disks; piston-heads upon the rod working within chests secured to the frame; pipes connecting the pump and the chests; and means for directing pressure into either of the chests.
5. The combination with a frame; of a hollow propeller-shaft journaled therein and provided with transversely-extending slots; a 15 slideable sleeve upon said shaft; friction-disks secured at the ends of the sleeve; a cross-pin within each disk and a slot of the propeller- shaft; a rod engaged by each cross-strip; 20 chests secured to the frame and inclosing the opposite ends of the rod; and a piston-head secured to each end of said rod.
6. The combination with a frame; of a hollow propeller-shaft journaled therein; friction-disks 25 slidably mounted upon the shaft and movable therewith; a rod connecting the disks; a piston-head at each end of the rod; a chest inclosing each piston-head; a reservoir; an escape-valve thereto; and pipes connecting the reservoir and each of the chests.
- In testimony whereof I affix my signature in presence of two witnesses.

WILLIAM LAY.
